UNITED STATES PATENT OFFICE.

HOWELL D. PRATT, OF PHILADELPHIA, PENNSYLVANIA, ASSIGNOR TO LINK-BELT COMPANY, OF CHICAGO, ILLINOIS, A CORPORATION OF ILLINOIS.

BALLAST-CLEANING MACHINE.

1,404,999.

Specification of Letters Patent. Patented Jan. 31, 1922.

Application filed November 3, 1919. Serial No. 335,360.

To all whom it may concern:

Be it known that I, HOWELL D. PRATT, a citizen of the United States, residing at Philadelphia, in the county of Philadelphia and State of Pennsylvania, have invented a certain new and useful Improvement in Ballast-Cleaning Machines, of which the following is a specification.

My invention relates to improvements in machines for mechanically cleaning and screening railroad ballast. One object of my invention is to provide a new and improved form of machinery which will be self-propelled and which will move forward automatically at a rate bearing a proper relation to the speed of excavation and screening so that a small crew may be used and that crew may limit its activities to keeping the machine in operation and feeding ballast to it from between individual ties so that when the machine has cleaned the ballast from between the line of track or alongside a line of track, it will also have cleaned a certain amount of ballast from between the individual ties of each track thus adding to the effectiveness of the cleaner. Another object is to provide a power driven ballast cleaning machine the units of which are small and light enough so that no extra crew is needed beyond that ordinarily operating the machine, for handling it and moving it into and out of operating position. Another object, of course, is to provide such a machine as will be safely positioned in the clearance space between two railroad tracks or alongside a railroad track and so that it will not be necessary to move it away from its working position when a train goes by. Another object is to provide means for automatically guiding the machine as it moves forward so as to keep it in the clearance space and prevent it from moving laterally toward the center line of either track or toward the center line of any track along which it works, which movement might, if not prevented, bring the machine out of the clearance space into the danger zone.

In order to accomplish these objects, I provide a flat low frame resting partially upon the ground or the surface of the ballast, or the surface of the ties in the ballast, and associate with it a toothed driving belt or belts, which belts carry part or all of the load and are in engagement for a portion of

their length, with the supporting surface so when they are moved and travel around sprockets on the frame, being driven by the power source, the apparatus will move forward. I provide a single power source which drives these belts and operates an excavator extending down below the surface of the material and adapted to carry material up above the surface and discharge it on the screen. The screen and excavator are both driven in unison from the single motive device. After the ballast is cleaned by the screen, it passes over beneath the frame back into the space beneath the track and the fines which have been taken out by the screen drop into a box beneath the screen whence they may be removed.

As the machine is moved forward, it is guided to prevent lateral movement and preserve parallelism with the tracks, by guiding members which engage one or more of the rails of the track and which may engage either the web of the rail or the upper surface.

I have shown a preferred form of guiding means wherein rollers engage the outside walls of the webs of the two inner rails of each track, and means are provided whereby when this roller comes to a fish plate or angle bar, it tips back throwing another roller in front into engagement with the rail thus jumping the fish plate. This makes sure of the guiding independent of any irregularities on the surface of the web against which the guiding member travels.

In order that the different parts of the device may be light enough for the working crew to pick them up when through work, the gasoline engine which generates the power together with the generator and reel of cable are mounted on a single fixed frame which is itself of such size that it is entirely within the clearance space and the screen device travels forward doing its work and drawing out the cable. When the cable is all drawn out, the crew carries the generator set forward winding up the cable and the cleaner again moves forward taking another bite. In actual practice, it is possible to operate the device by having the ballast cleaning part move constantly forward and by having the power generating part of the apparatus move forward by series of separate steps.

My invention is illustrated more or less diagrammatically in the accompanying drawings wherein—

- 5 Figure 1 is a side elevation;
- 5 Figure 2 is a plan view;
- 10 Figure 3 is an end view with parts in section;
- 10 Figure 4 is a diagrammatic showing of the entire apparatus;
- 15 Figure 5 is a plan view of the preferred form of the guiding apparatus;
- 15 Figure 6 is a section through the propelling apparatus;
- 20 Figure 7 is a detail taken from Figure 6;
- 20 Figure 8 is a cross section through the lower run of one of the belt treads.
- 25 Like parts are indicated by like characters throughout.
- 25 The main supporting frame is made up of two side members A A, turned upwardly at their forward ends as at A¹ A¹ and having broad under bearing surfaces as indicated. These members are tied together by cross braces A² A³ and plates A⁴ A⁴ which latter extend inwardly from the cross members A¹ A¹ toward the center of the apparatus and terminate where they engage the inner side frame members A⁵ A⁵ which extend forwardly and upwardly to support 30 at their forward upward ends, the brackets A⁶ A⁶. These brackets have pivoted thereon, the side members A⁷ A⁷ of the excavating ladder and carry the quadrants A⁸ notched as indicated, to be engaged by a pin 35 A⁹ in the side frames of the excavating ladder whereby the excavating ladder itself may be locked in any angular position. A¹⁰ A¹⁰ are slidably mounted guide arms projecting outwardly from the frame members 40 A A, they carry rail web engaging rollers A¹¹, and are yieldingly thrust outward by spring A¹². Their inward movement is so limited that while they have sufficient excursion to permit the rollers to pass by the 45 angle bars, the apparatus is always contained within the clearance space. A¹⁴ is a baffle plate which is supported on the rear end of the quadrants A⁸ and prevents the overthrow of dirt and stones.
- 50 B is a head sprocket. B¹ is a tail sprocket. Mounted on the excavating ladder B² is an excavating chain passing over the head and tail sprockets and carrying buckets B³ which buckets pick up dirty ballast B⁴ and dis- 55 charge it onto a reciprocating screen B⁵. The fines which pass through the screen are caught in a dust box B⁶ extending down below the frame into the hole made by the removal of the ballast, and the clean ballast 60 passes back over the screen to fill up the hole after the dust box has passed. B⁷ is a driving sprocket associated with the head sprocket B and it is driven by means of a sprocket chain B⁸ from a jack shaft B⁹ 65 which jack shaft is mounted for rotation on

the frame A⁵. This jack shaft is driven by means of a gear B¹⁰ and a pinion B¹¹ from the eccentric shaft B¹² mounted for rotation also on the frame A⁵. B¹³ B¹³ are eccentrics on the shaft B¹² engaging eccentric straps B¹⁴ which in turn are mounted on the eccentric rods B¹⁵ pivoted to and driving the screen B⁵. B¹⁶ is a motor. It drives the eccentric driving shaft B¹² by means of a silent chain B¹⁷ to furnish the power to operate the excavator and reciprocate the screen. 75

The forward end of the apparatus is supported on the runner-like under surfaces of the side frames A A. The rear end is supported on a kind of caterpillar track 80 arrangement made up of the endless toothed link belt treads C, one under each of the frames A. These treads travel over the forward idler sprockets C¹ and the rearward driving sprockets C², one at either end of the driving shaft C³ C⁴. These driving shafts abut at their ends and have keyed to the inner ends, the clutch wheels C⁵ C⁶. C⁷ is a driving lever pivoted on said shafts and mounted for oscillation between the wheels. 85 Pivoted on this lever are ratchet members C⁸ C⁹ in opposition to the wheels C⁵ C⁶. These ratchet members normally engage these wheels and when both are in operation, the two shafts are driven by the reciprocation of the driving lever, but if it is desired to drive only one of the traction members this may be accomplished by disengaging one of the ratchets or the entire drive 90 may be discontinued by disengaging both the ratchets. Extending rearwardly from the two eccentric straps B¹⁴ is a yoke C¹⁰ and this yoke has a rearwardly extending projection C¹¹ pivoted to the driving lever, 95 the angle of movement of which may be varied by varying the pivot point of the eccentric strap on the driving lever. 100

The screen B⁵ is reciprocated by the rotation of the shaft B¹² and the movement of the eccentric members B¹³, which are linked 110 to the screen by the yoke or parallel members B¹⁵ B¹⁵ shown in Figure 2.

In Figure 5 is shown the modified preferred form of guiding mechanism. D is the railroad rail cut away to show the web at 115 D¹. D² is a guide arm pivoted on the frame member A¹ and having rollers D³ adapted yieldingly to be pressed against the web D¹ by the heavy spring D⁴. It must be understood that there is a similar assembly on the other side of the apparatus and that the size and relation of the parts are such that the pivoted arms are substantially perpendicular to the axis of movement. The arm D² is prevented from swinging clear around by 120 the stop D⁸. These springs are stiff and heavy and as the apparatus moves forward, these rollers are firmly held against the rail webs and prevent lateral movement of the apparatus. When the rollers strike an angle 125 130 135

plate, however, as at D¹⁰, they cannot pass by without bending back and compressing the spring D⁴ and this would permit the apparatus to move toward the rail were it not for the auxiliary arm D⁵ pivoted on the frame member A¹ and having a roller D⁶ adapted to engage the rail web D¹ when the roller D³ moves back to clear the angle plate, and this roller D⁶ is at that time forced into engagement with the web of the rail by the rotation of the arm D² transmitted through the tie link D⁷. For normal operation, the position of the parts is as shown in full lines but when the guide roller reaches an angle plate, the further forward movement of the apparatus brings the parts in the position shown in dotted lines until the angle plate is passed, when the spring snaps the guide back into the full line position.

In Figure 4, is shown a diagrammatic side elevation of the apparatus and associated parts. At E, we have the excavating machine with its electric motor connected by the cable E¹ which may be wound on or off the reel E² with the generator E³ on a portable frame E⁴ which generator is driven by a gasoline engine E⁵ and provides the power to operate the motor on the ballast cleaning machine. The cable on the reel is of considerable length. The motor generator set is placed at rest between the tracks within the clearance space immediately behind the ballast cleaner. The engine is started and as soon as it comes up to speed, the ballast cleaner is put into operation. It propels itself forward doing its work, drawing the cable off the reels until the cable is all pulled out. The crew then moves the motor generator set up again by hand or by lifting it onto the hand car, winding on the cable until the motor generator set is up to the ballast cleaner. This may be done without stopping the operation. The motor generator set is placed on the ballast between the tracks again and the operation is repeated. This may go on indefinitely.

It is evident that I have shown in my drawings an operative device, still many changes might be made in size, shape, or arrangement of parts without departing materially from the spirit of my invention, and I wish, therefore, that they may be regarded as in a sense, diagrammatic.

The use and operation of my invention are as follows:

The motor generator set and the ballast cleaning machine will normally be carried on hand cars or trucks from the storage place to the place where they are to be used. The crew will dig out the ballast from between the tracks for a short distance so as to make a hole in which the ballast cleaner may operate. The ballast cleaner will be placed on the ballast above this hole with

the excavator in working position. The crew will then place the motor generator set in the space between the two tracks immediately behind the ballast cleaner and couple up the cable between the motor generator set and the cleaner and start the gas engine. The operator then starts the electric motor to operate the ballast cleaner. The crew will feed ballast down from between the ends of the individual ties of the two tracks into the space where the ballast excavator may dig it up thus the ballast cleaner will attack not only the ballast in the clear space between the two tracks, but also some of the ballast between individual ties of each track. As the cleaner propels itself forward, this clean ballast is returned to the hole behind the point of excavation and the operators can move part of it back into the space between the individual ties, so the process continues with the ballast cleaner moving forward under its own power. If a train goes by, the crew merely steps to one side and the cleaner can continue its operation because it is in the space between the tracks where no part of any car ever comes. The ballast cleaner progresses forward drawing its power through the cable leading to the motor generator set, but the motor generator set remains at rest until the cable is all payed out. Then the crew lifts up the motor generator set and puts it down behind the ballast cleaner and repeats the process. This will continue indefinitely until the job is done.

It will be evident that with the power available for propelling the ballast cleaner, it might under some conditions be desirable to mount the motor generator set on runners and have it hauled along the right of way by the forward moving ballast cleaner, and this, under some conditions, would be done.

I claim:

1. The combination with a machine for cleaning ballast arranged to travel in the clear space between the tracks of a double track railway, of means engaging one of the track rails for guiding it along a path parallel with the track, the entire mechanism being so arranged and positioned that trains can pass on either track without interfering therewith.

2. The combination with a machine for cleaning ballast arranged to travel in the clear space between the tracks of a double track railway, of means engaging one of the rails of each track for guiding it along a path parallel with the track, the entire mechanism being so arranged and positioned that trains can pass on either track without interfering therewith.

3. The combination with a machine for cleaning ballast arranged to travel in the clear space between the tracks of a double track railway, of yielding means engaging

one of the track rails for guiding it along a path parallel with the track, the entire mechanism being so arranged and positioned that trains can pass on either track without interfering therewith.

4. The combination with a machine for cleaning ballast arranged to travel in the clear space between the tracks of a double track railway, of yielding means engaging 10 one of the rails of each track for guiding it along a path parallel with the track, the entire mechanism being so arranged and positioned that trains can pass on either track without interfering therewith.

15 5. The combination with a machine for cleaning ballast arranged to travel in the clear space between the tracks of a double track railway, of means engaging the web of one of the track rails for guiding it along a path parallel with the track, the entire mechanism being so arranged and positioned that trains can pass on either track without interfering therewith.

20 6. The combination with a machine for cleaning ballast arranged to travel in the clear space between the tracks of a double track railway, of means engaging the web of one of the rails of each track for guiding it along a path parallel with the track, the entire mechanism being so arranged and positioned that trains can pass on either track without interfering therewith.

25 7. The combination with a machine for cleaning ballast arranged to travel in the clear space between the tracks of a double track railway, of yielding means engaging the web of one of the track rails for guiding it along a path parallel with the track, the entire mechanism being so arranged and positioned that trains can pass on either track without interfering therewith.

30 8. The combination with a machine for cleaning ballast arranged to travel in the clear space between the tracks of a double track railway, of yielding means engaging the web of one of the rails of each track for guiding it along a path parallel with the track, the entire mechanism being so arranged and positioned that trains can pass on either track without interfering therewith.

35 9. The combination with a machine for cleaning ballast arranged to travel in the clear space between the tracks of a double track railway, of means engaging the web of one of the track rails for guiding it along a path parallel with the track, and automatic means associated with the guiding means for compensating for any irregularities in the 40 surface of the web met by the guiding means as they travel along, the entire mechanism being so arranged and positioned that trains can pass on either track without interfering therewith.

45 10. The combination with a machine for

cleaning ballast arranged to travel in the clear space between the tracks of a double track railway, of means engaging the web of one of the rails of each track for guiding it along a path parallel with the track, and 70 automatic means associated with the guiding means for compensating for any irregularities in the surface of the web met by the guiding means as they travel along, the entire mechanism being so arranged and positioned 75 that trains can pass on either track without interfering therewith.

11. The combination with a machine for cleaning ballast arranged to travel in the clear space between the tracks of a double track railway, of yielding means engaging the web of one of the track rails for guiding it along a path parallel with the track, and 80 automatic means associated with the guiding means for compensating for any irregularities in the surface of the web met by the guiding means as they travel along, the entire mechanism being so arranged and positioned 85 that trains can pass on either track without interfering therewith.

12. The combination with a machine for cleaning ballast arranged to travel in the clear space between the tracks of a double track railway, of yielding means engaging the web of one of the rails of each track 95 for guiding it along a path parallel with the track, and automatic means associated with the guiding means for compensating for any irregularities in the surface of the web met by the guiding means as they travel along, 100 the entire mechanism being so arranged and positioned that trains can pass on either track without interfering therewith.

13. The combination with a machine for cleaning ballast arranged to travel in the clear space between the tracks of a double track railway, of means engaging one of 105 the track rails for guiding it along a path parallel with the track, said means being adapted to guide the apparatus along a straight path independent of any irregularities in the rail surface engaged by it.

14. The combination with a machine for cleaning ballast arranged to travel in the clear space between the tracks of a double 115 track railway, of means engaging the web of one of the track rails for guiding it along a path parallel with the track, said means being adapted to guide the apparatus along a straight path independent of any irregularities in the rail surface engaged by it.

15. The combination with a machine for cleaning ballast arranged to travel in the clear space between the tracks of a double track railway, of means engaging the web 120 of one of the track rails for guiding it along a path parallel with the track.

16. The combination with a machine for cleaning ballast arranged to travel in the clear space between the tracks of a double 125

- track railway, of means engaging the web of one of the rails of each track for guiding it along a path parallel with the track. 17. The combination with a machine for 5 cleaning ballast arranged to travel in the clear space between the tracks of a double track railway, of yielding means engaging the web of one of the track rails for guiding it along a path parallel with the track. 18. The combination with a machine for 10 cleaning ballast arranged to travel in the clear space between the tracks of a double track railway, of yielding means engaging the web of one of the rails of each track, 15 for guiding it along a path parallel with the track. 19. The combination with a machine for 20 cleaning ballast arranged to travel in the clear space between the tracks of a double track railroad, of guiding means therefor comprising two pivoted arms, yielding means for thrusting the end of one of them into engagement with the rail web and a 25 connection between them whereby only one arm at a time can come into engagement with the web. 20. The combination with a machine for 30 cleaning ballast arranged to travel in the clear space between the tracks of a double track railroad, of guiding means therefor comprising two pivoted arms, yielding means for thrusting the end of one of them into engagement with the rail web and a 35 connection between them whereby only one arm at a time can come into engagement with the web, said connection comprising a link pivoted at either end on one of said arms, the length of the link being such that the arms are outwardly divergent. 21. The combination with a machine for 40 cleaning ballast arranged to travel in the clear space between the tracks of a double track railroad, of guiding means therefor comprising two pivoted arms, yielding 45 means for thrusting the end of one of them into engagement with the rail web and a connection between them whereby only one arm at a time can come into engagement with the web, there being a pair of such arms 50 on either side of the machine whereby the machine is guided between the inner rails of each of the two tracks. 22. The combination with a machine for 55 cleaning ballast arranged to travel in the clear space between the tracks of a double track railroad, of guiding means therefor comprising two pivoted arms, yielding means for thrusting the end of one of them into engagement with the rail web and a 60 connection between them whereby only one arm at a time can come into engagement with the web, said connection comprising a link pivoted at either end on one of said arms, the length of the link being such that the 65 arms are outwardly divergent, there being a pair of such arms on either side of the machine whereby the machine is guided be- 130
- being a pair of such arms on either side of the machine whereby the machine is guided between the inner rails of each of the two tracks. 23. The combination with a machine for 70 cleaning ballast arranged to travel in the clear space between the tracks of a double track railroad, of guiding means therefor comprising two pivoted arms, yielding means for thrusting the end of one of them 75 into engagement with the rail web and a connection between them whereby only one arm at a time can come into engagement with the web, the distance between the rail engaging ends of said arms being greater 80 than the normal length of the angle bars used to tie the rails together. 24. The combination with a machine for 85 cleaning ballast arranged to travel in the clear space between the tracks of a double track railroad, of guiding means therefor comprising two pivoted arms, yielding means for thrusting the end of one of them into engagement with the rail web and a 90 connection between them whereby only one arm at a time can come into engagement with the web, said connection comprising a link pivoted at either end on one of said arms, the length of the link being such that the arms are outwardly divergent, the distance between the rail engaging ends of 95 said arms being greater than the normal length of the angle bars used to tie the rails together. 25. The combination with a machine for 100 cleaning ballast arranged to travel in the clear space between the tracks of a double track railroad, of guiding means therefor comprising two pivoted arms, yielding means for thrusting the end of one of them 105 into engagement with the rail web and a connection between them whereby only one arm at a time can come into engagement with the web, there being a pair of such arms on either side of the machine whereby the machine is guided between the inner rails of each of the two tracks, the distance 110 between the rail engaging ends of said arms being greater than the normal length of the angle bars used to tie the rails together. 26. The combination with a machine for 115 cleaning ballast arranged to travel in the clear space between the tracks of a double track railroad, of guiding means therefor comprising two pivoted arms, yielding 120 means for thrusting the end of one of them into engagement with the rail web and a connection between them whereby only one arm at a time can come into engagement with the web, said connection comprising a link 125 pivoted at either end on one of said arms, the length of the link being such that the arms are outwardly divergent, there being a pair of such arms on either side of the machine whereby the machine is guided be- 130

tween the inner rails of each of the two tracks.

27. The combination with a machine for cleaning ballast arranged to travel in the clear space between the tracks of a double track railroad, of guiding means therefor comprising two pivoted arms, yielding means for thrusting the end of one of them into engagement with the rail web and a connection between them whereby only one arm at a time can come into engagement with the web, the relation between the arms being such that when the rearmost arm is in engagement with the rail connecting means and thereby raised out of contact with the rail web, the end of the forward arm is drawn into engagement with the rail web.

28. The combination with a machine for cleaning ballast arranged to travel in the clear space between the tracks of a double track railroad, of guiding means therefor comprising two pivoted arms, yielding means for thrusting the end of one of them into engagement with the rail web and a connection between them whereby only one arm at a time can come into engagement with the web, the relation between the arms being such that when the rearmost arm is in engagement with the rail connecting means and thereby raised out of contact with the rail web, the end of the forward arm is drawn into engagement with the rail web.

29. The combination with a machine for cleaning ballast arranged to travel in the clear space between the tracks of a double track railroad, of guiding means therefor comprising two pivoted arms, yielding means for thrusting the end of one of them into engagement with the rail web and a connection between them whereby only one arm at a time can come into engagement with the web, there being a pair of such arms on either side of the machine whereby the machine is guided between the inner rails of each of the two tracks, the relation between the arms being such that when the rearmost arm is in engagement with the rail connecting means and thereby raised out of contact with the rail web, the end of the forward arm is drawn into engagement with the rail web.

30. The combination with a machine for cleaning ballast arranged to travel in the clear space between the tracks of a double track railroad, of guiding means therefor comprising two pivoted arms, yielding means for thrusting the end of one of them into engagement with the rail web and a connection between them whereby only one arm at a time can come into engagement with the web, said connection comprising a link pivoted at either end on one of said arms, the length of the link being such that

the arms are outwardly divergent, there being a pair of such arms on either side of the machine whereby the machine is guided between the inner rails of each of the two tracks, the relation between the arms being such that when the rearmost arm is in engagement with the rail connecting means and thereby raised out of contact with the rail web, the end of the forward arm is drawn into engagement with the rail web.

31. The combination with a machine for cleaning ballast arranged to travel in the clear space between the tracks of a double track railway, having a reciprocating ballast cleaning screen and means for driving it, of a propelling member, a ratchet clutch associated therewith, and a connection between such ratchet clutch and the screen driving mechanism whereby the apparatus is forwardly propelled as the screen operates.

32. The combination with a machine for cleaning ballast arranged to travel in the clear space between the tracks of a double track railway, of a reciprocating screen, an eccentric shaft, and a driving connection between them, means for rotating the shaft, a running gear for the machine, and a driving connection between it and the screen driving means.

33. The combination with a machine for cleaning ballast arranged to travel in the clear space between the tracks of a double track railway, of a reciprocating screen, and eccentric shaft, and a driving connection between them, means for rotating the shaft, a running gear for the machine, and a driving connection between it and the screen driving means, said connection comprising a ratchet clutch lever and a link connecting it and the eccentric driving connection.

34. The combination with a machine for cleaning ballast arranged to travel in the clear space between the tracks of a double track railway, of a reciprocating screen, and eccentric shaft, and a driving connection between them, means for rotating the shaft, a running gear for the machine, and a driving connection between it and the screen driving means, said connection comprising a ratchet clutch lever and a link connecting it and the eccentric driving connection, the length of said lever being adjustable to vary the travel of the machine.

35. The combination with a machine for cleaning ballast arranged to travel in the clear space between the tracks of a double track railway, of a sliding support therefor, and means for moving said machine forward upon such sliding support.

36. The combination with a machine for cleaning ballast arranged to travel in the clear space between the tracks of a double track railway, of a sliding support therefor, and means for moving said machine forward

- upon such sliding support, said means comprising an endless ground engaging belt and means for driving it. 50
37. The combination with a machine for 5 cleaning ballast arranged to travel in the clear space between the tracks of a double track railway, of a sliding support therefor, and means for moving said machine forward upon such sliding support, said means comprising an endless ground engaging belt and 10 means for driving it, the forward end of the machine only, being supported on the sliding support, the rear end being supported on the belt. 15
38. The combination with a machine for 15 cleaning ballast arranged to travel in the clear space between the tracks of a double track railway, of supporting runners beneath the forward end of the machine and means 20 located toward the rear of the machine for propelling it forward. 25
39. The combination with a machine for 25 cleaning ballast arranged to travel in the clear space between the tracks of a double track railway, of supporting runners beneath the forward end of the machine and means 30 located toward the rear of the machine for propelling it forward, said means comprising an endless ground engaging belt. 35
40. The combination with a machine for 35 cleaning ballast arranged to travel in the clear space between the tracks of a double track railway, of supporting runners beneath the forward end of the machine and means 40 located toward the rear of the machine for propelling it forward, said means comprising an endless ground engaging belt, said belt being interposed between the ground and a rearward continuation of the runners, 45 which continuation of the runners forms a sliding bearing on the upper surface of the ground engaging belt. 50
41. In an excavating machine, a frame 55 supporting runner beneath the forward end of the machine and a ground engaging driving belt beneath the rear end of the machine, said belt being in line with the runner, the weight of the machine being applied to the 60
- ground engaging driving belt by rearward extensions of said runners. 55
42. A machine for cleaning ballast arranged to travel in a clear space between the tracks of a double track railway, comprising an excavating, propelling and cleaning machinery and driving motor and a motor generator set, and a flexible extensible connection between said motor and said generator set. 65
43. The combination with a machine for 60 cleaning ballast arranged to travel in a clear space between the tracks of a double track railway, of means for guiding it along a path parallel with the track, the entire mechanism being so arranged and positioned that trains can pass by on either track without 65 interfering therewith, means for cleaning the ballast, and means for advancing the entire mechanism, in response to movement of the ballast cleaning means. 70
44. The combination in a machine for 70 cleaning ballast, of a frame arranged to travel in the clear space between the tracks of a double track railway, means on said frame for removing the ballast from the roadbed, means for screening the ballast and 75 returning it to the roadbed, and means associated with the ballast removing means for propelling the frame forwardly as it works, the entire mechanism being located on the frame in such position that trains can pass 80 on either track without interfering with the frame and the mechanism carried thereby. 85
45. The combination with a machine for 85 cleaning ballast arranged to travel in the clear space between the tracks of a double track railway, of ballast excavating and ballast cleaning means, a driving mechanism therefor, and means driven thereby for propelling the apparatus as it works. 90

In testimony whereof, I affix my signature 90
in the presence of two witnesses this 29th
day of September, 1919.

HOWELL D. PRATT.
